CLAIM

The ornamental design for an electric kettle base, as shown, and described.

DESCRIPTION

FIG. 1 is a perspective view of the electric kettle base; FIG. 2 is a top view thereof; FIG. 3 is a bottom view thereof; FIG. 4 is a front view thereof; FIG. 5 is a rear view thereof; FIG. 6 is a left side view thereof; FIG. 7 is a right side view thereof; and, FIG. 8 is a perspective view thereof in a use environment. The broken lines in the drawing views represent unclaimed portions of the electric kettle base, which forms no part of the claimed design. Further, the kettle shown in a use environment forms no part of the claimed design.

1 Claim, 8 Drawing Sheets
